[57] ABSTRACT

Apparatus for automatically controlling the weight on a rotary drilling bit, including cable drum, drum rotation monitor, deadline sensor, brake for the drum, brake actuator, and brake release, and characterized by the improvement of a gate for passing and stopping a brake release signal; a brake release signal generator for generating a brake release signal responsive to excessive tensional force in the cable deadline; and signal length modifier connected with the drum rotation monitor and the gate for stopping passage of the brake release signal responsive to rotation of the cable drum. Two specific embodiments are also described.

APPARATUS FOR AUTOMATICALLY CONTROLLING WEIGHT-ON-BIT

BACKGROUND OF THE INVENTION

1. Field of the Invention weight string

This invention relates to apparatus for automatically controlling a parameter in drilling a wellbore into subterranean formations. More particularly, the invention relates to apparatus for automatically controlling the weight on the drilling bit, called weight-on-bit, during drilling of a wellbore into subterranean formations by a rotary drilling rig.

2. Description of the Prior Art

A wide variety of methods and apparatus have been employed for automatically controlling weight-on-bit, but such prior art methods and apparatus have disadvantages that are overcome by this invention. For example, the prior art apparatus has been complex, frequently requiring major modifications for installation on certain drilling rigs, and has not been readily installable on any rig with only minor modifications. The prior art apparatus and methods have employed attempts to control weight-on-bit by automatically controlling the usual brake lever of the draw works; but, because of the inherent lag of the control system and the action of the brake system and lever, over controlled and produced erratic drilling and wellbore deviations. Specifically, the prior art systems have not had a sufficient degree of flexibility and adjustability to effect the desired successful and economically feasible automation of the conventional rotary drilling rigs. A couple of the prior art systems have attempted to provide a partial brake release signal so as to only release the brake part of the way to the full release position. The latter systems have not been totally successful, primarily because of the tendency of a cable drum to wear unevenly such that varying lengths of cable are released from different parts of the drum when a partial brake release signal is employed, effecting nonuniform payout even with a constant signal level.

BRIEF DESCRIPTION OF THE DRAWINGS

FIG. 1 is a diagrammatic view of a drilling control apparatus on a rotary drilling rig employing an embodiment of this invention.

FIG. 2 is a partial schematic block diagram illustrating one embodiment of the signal length modifier means of FIG. 1.

FIG. 3 is a partial electrical schematic diagram depicting the proportional response means in the embodiment of FIG. 2.

FIG. 4 is a partial schematic block diagram illustrating another embodiment of the signal length modifier means of FIG. 1.

DESCRIPTION OF PREFERRED EMBODIMENTS

It is an object of this invention to provide improved apparatus for automatically controlling weight-on-bit that has one or more of the following advantageous features not heretofore provided:

1. may be installed and employed on any rotary drilling rig with only minor modifications;
2. provides a brake release signal that is either full "on" or full "off" to obviate attempting to control a worn cable drum by partial control signals; yet is adjustable in length and in effect, both at its front end and at its trailing edge;

3. in a specific embodiment, provide manual adjustment at both the front end and trailing edge of a brake release signal to better compensate for inertia of the brake system and the control system on a rotary drilling rig; and

4. in another specific embodiment provide a manual adjustment at the front end and an inverse proportioning response at the trailing edge of a brake release signal to compensate for inertia of the brake and control systems.

Referring to FIG. 1, the numeral 11 designates the conventional crown block comprising a plurality of sheaves mounted at the top of a rotary drilling rig (not shown). A travelling block 13 is suspended from the crown block 11 by means of a cable system 15 providing the requisite mechanical advantage for raising and lowering the large weights of the drill string 17. As is well known, the drill string 17 is connected with the travelling block 13 by a kelly 19 traversing a rotary table 21 for rotating the bit. Suitable drilling mud circulation means typified by hose 23 may be employed for circulating drilling mud into and from the wellbore, carrying cuttings and the like.

The cable system comprises a tensioned cable having a first end, or deadline, 25 that is non-moving, or "dead," in normal operation. The second, or "fast," end 27 of the cable moves most rapidly in normal operation, as by being spooled onto or from cable drum 29. Specifically, the deadline 25 is wound around an eccentrically mounted spool 31 and connected with an anchored cable storage drum 33 to facilitate spooling off worn cable and replacing it with new cable.

As is well known, the cable drum 29 is rotated in one direction by suitable power equipment (not shown) for raising the travelling block 13 and the drill string 17. The cable drum 29 is rotated in the opposite direction by the weight of the drill string to pay out cable and lower the weight of the drill string onto a drilling bit 35 carried at the lower end of the drill string 17. Pay out of the cable from the cable drum 29 is controlled by a brake 37. Conventionally, rotary drilling rigs will have a brake lever 39 for controlling the brake. Inattention by a driller or different drillers effected a wide variance in the straightness, as well as the rate of drilling, for well recognized reasons. To facilitate installation of the automatic control apparatus on existing rigs, therefore, the brake lever 39 is incorporated into the control apparatus. Specifically, a brake applying means is connected with the brake 37 via the brake lever 39 for automatically restoring and maintaining the brake applied when the brake is not being released by a brake release means; the brake applying means being illustrated in the form of a spring 41 connected with support 43 such as the floor of a drilling rig. Thus, the brake is normally applied and prevents rotation of the cable drum 29 to pay out cable. A brake release means incorporating a fluid-powered ram 45 connected with a suitable support 47 is connected with the brake 37 via brake lever 39 for releasing the brake and allowing a pay out of the cable in response to a brake release signal. Specifically, the ram 45 is connected with a suitable motive fluid supply source; such as, a rig's pneumatic air supply; via conduit 49 and solenoid-operated, three-way valve 51. The three-way valve 51 supplies motive fluid under pressure to release the brake, or releases the pressure to the atmosphere to allow the spring 41 to apply the brake. The three-way valve 51 is connected with sole-

60
55
60
65

noid 53, as indicated by dashed lines 55. Suitable auxiliary valves such as quick release valves may be employed to reduce the lag in the brake release system, if desired.

During the actual drilling operation it is necessary to apply at least part of the weight of the drill string 17 to the bit 35 to secure proper rate of penetration of the formation and proper inclination of the wellbore, or hole. Moreover, different formations require different weights-on-bit. Improper weight on the bit can result in damage to the drill bit with the expense of having to prematurely pull the bit from the hole, crooked holes, damage to drill pipe, cave-ins and other difficulties effecting sticking of the drill pipe, and the like. Thus, efficiently controlling the weight on the bit is one of the most important factors in improving the proper drilling of wellbores into the subterranean formation. The apparatus of this invention for automatically controlling weight on a bit includes, in addition to the elements described hereinbefore, sensor means 59, signal generator, or generating, means 61, gate means 63, drum rotation monitor means 65, and signal length modifier means 67.

The sensor means 59 is responsively connected with the tensioned deadline 25 of the cable so as to sense the tension therein. As indicated hereinbefore, the tension in the deadline is a function of the weight on the travelling block 13 and is inversely related to the weight on the bit. Expressed otherwise, the greater the portion of the weight of the drill string that is being sustained by the travelling block 13, the lesser the portion of the weight of the drill string 17 that is bearing on the drill bit 35. Accordingly, as the length of the drill string is increased, as by adding joints of tubing, the control tension in the deadline, about which the sensor means controls, is altered, or zeroed, to maintain the desired weight on the bit. An example of establishing the desired control tension is described in the operation of the apparatus hereinafter. Any of the conventional sensor means may be employed. As illustrated, however, the sensor means 59 includes a conventional load indicator 68 with its sensor incorporating a movable iron core employed in a conventional linear differential transformer arrangement for great sensitivity in detecting small changes in deformation of the deadline 25 under tension.

The signal generator means 61 is connected with the sensor means 59 and the gate means 63. Responsive to the sensing of a tension greater than a predetermined control tension by the sensor means 59, the signal generator means 61 generates a brake release signal and actuates the gate means to pass the brake release signal to the brake release means, comprising the solenoid 53, three-way valve 51 and ram 45. The signal generator means includes a controller 69 and a signal generator 71.

The controller 69 may comprise any of the conventional elements that are compatible with the output from the sensor means 59 and will effect an on-off signal. As illustrated, the controller 69 comprises a phase detector 73 and a level detector 75. The phase detector 73 is the most sensitive known means of comparing, via a bridge circuit arrangement, the sensor-connected linear differential transformer with a standard matched linear differential transformer. This combination of sensor means 59 and phase detector 73 has great sensitivity and detects the small changes in tension in the

deadline 25. Any on-off switch means that is compatible with the phase detector 73 may be employed as the level detector 75. As illustrated, the level detector 75 comprises a Schmitt trigger circuit that is connected with the phase detector 73 and with the signal generator to turn on the signal generator 71 upon receipt of a voltage output above a predetermined control voltage from phase detector 73.

The signal generator 71 may produce a continuous signal for use as a brake release signal, or it may produce a plurality of pulses for use as the brake release signal. Any of the conventional signal generators that produce the desired pulse and that are compatible with the output from the level detector 75 may be employed. As illustrated, the signal generator 71 is an oscillator. In a preferred embodiment, it comprises a unijunction oscillator. The oscillator produces pulses of a time duration in the range of about one-fourth to one-half second and repeats at a frequency in the range of one pulse each 1-3 seconds.

The gate means 63 may comprise any compatible element that can be turned on or off for passage, or conduction, of the brake release signal from the signal generating means 61 to the brake release means. An economical and unsatisfactory gate means has been found to comprise a multivibrator such as a bistable multivibrator that can be turned on by the signal generator means 61 and turned off by the signal length modifier means 67. A preferred multivibrator is a monostable multivibrator which effects a pulse length of a predetermined time duration such that it will automatically terminate the pulse serving as the brake release signal after the predetermined time duration even if the signal length modifier means should fail to operate. Thus, the monostable multivibrator provides an inherent safety factor, or fail-safe device. As employed in a preferred embodiment of this invention, the multivibrator is interconnected with a potentiometer, such as Helipot, illustrated as calibrated dial 77, FIGS. 2 and 4. The Helipot allows adjusting the time interval, or the duration, of the pulse from the monostable multivibrator by manual adjustment of the calibrated dial 77. The Helipot provides for an adjustment at the front end of the brake release signal to compensate for the inherent dynamics and lag characteristics of the brake, the brake lever, and the control system on the particular rotary drilling rig on which it is installed. Thus, by a brief period of trial and error operation, the most nearly optimum control can be effected for a given drilling rig operating under a given drilling condition.

The drum rotation monitor means 65 may comprise any control unit which feeds back intelligence responsive to movement of the cable as effected by rotation of the drum. Conventionally, such units employ a movement detection wheel 79 which is mounted on the extended end of a main shaft 81. The wheel 79 is adapted to engage a surface disposed near the periphery of the cable drum and, when engaged, rotate at a much greater rotational speed in revolutions per minute than the cable drum, because of the wide variance in their respective radii. The wheel 79 is in fixed engagement with the shaft 81 so that rotation of the wheel effects rotation of the shaft 81. The shaft 81 extends through a suitable housing and is journalled on bearings therein (not shown). Additionally, the main shaft 81 is pivotally mounted by a conventional structure so it can be pivoted so as to disengage from the cable drum for

operations other than normal drilling operation; for example, when a trip is being made to run a bit into or out of the wellbore. Since such drum rotation monitor means are conventional and do not, per se, comprise a part of this invention, no further detailed explanation need be given herein. It is sufficient to note that the main shaft is connected with a suitable means; such as, a rotary cam 83, FIGS. 3 and 4; in the signal length modifier means 67; as denoted by dashed line 85.

The signal length modifier means 67 is connected with the drum rotation monitor means 65 and with the gate means 63. Responsive to rotation of the cable drum 29, as monitored by cable drum rotation monitor means 65, the signal length modifier means 67 renders the gate means 63 nonconductive to stop passage of a brake release signal.

In the embodiment of FIG. 2, the signal length modifier means 67 comprises proportional response means 87 for stopping passage of the brake release signal after a time interval having a magnitude that is inversely proportional to the rate at which the drum starts to rotate. Any proportional response controller which is compatible with the output from the drum rotation monitor means 65; for example, by way of rotary cam 83; and which will yield an on-off output signal for control of gate means 63 may be employed to effect the proportional response means. As illustrated, the proportional response means 87 comprises a switch means 89 that is serially connected with a Paschal triangle-type filter network 91, and a level sensor 93. The drum rotation monitor means 65 is drivingly connected with the switch means 89 via rotary cam 83 and mechanically juxtaposed interconnection, indicated by dashed line 95. The rotary cam 83 may comprise any of the conventional cams having one or more eccentric lobes for converting the rotational movement of the shaft 81 of the drum rotation monitor means 65 into a reciprocal motion for effecting switching of the switch means 89.

FIG. 3 illustrates an electrical schematic diagram incorporating elements of the proportional response means 87. Therein, the level sensor 93 is illustrated as an electronic switch means, specifically transistor 97. The switch means 89 is shown incorporated into the Paschal triangle-type, or Paschal-type, filter network 91. The transistor 97 has a means such as base 99 for rendering it electrically conductive. The transistor 97 is serially connected with the gate means 63, such as the multivibrator, and a power source, illustrated as B+, for rendering the gate means nonconductive when the transistor 97 is rendered electrically conductive. Serially connected with the base 99 are biasing capacitor 101 and biasing resistor 103. The biasing resistor 103, as illustrated, is connected directly with the base 99. The biasing capacitor 101 is connected at its other side with the center pole 105 of the switch means 89. A discharging resistor 107 is connected with the juncture of the biasing resistor 103 and the biasing capacitor 101 and with a first contact 109 of the switch means 89 so as to discharge the biasing capacitor 101 when the switch means 89 connects the biasing capacitor 101 with the first contact 109. The second contact 111 of the switch means 89 is connected with electrical common, or ground, for charging the biasing capacitor 101 when the switch means connects the biasing capacitor 101 with the second contact 111. A second capacitor 113 and third resistor 115 are connected in parallel. The parallel-connected resistor 115 and capacitor 113

are serially connected with the power source B+ and with the juncture of the base 99 and the biasing resistor 103. The values of the capacitors and resistors are chosen such that the biasing capacitor 101 is charged more rapidly with more rapid switching of the switch means 89, as by a rapidly turning rotary cam 83, effected by rapid acceleration of the cable drum 29 as it begins to rotate. Thus, the speed with which the gate means 63 is turned off, or rendered electrically nonconductive, is proportional to the rate of rotation of the movement detecting wheel 79 monitoring rotation of the cable drum 29. Expressed in more conventional language, the time duration of a brake release signal from signal generator 71 has a magnitude that is inversely related to the rate of rotation of the wheel 79, or the rate at which switching by the switch means 89 is effected; the time duration being lessened, or shortened, by a greater switching rate; that is, by more rapidly opening and closing the switch means 89.

20 In operation, the apparatus is installed on a conventional rotary drilling rig as illustrated and drilling started. During drilling, the sensor means 59 detects a tension greater than the control tension and produces an output to controller 69. The controller 69 turns on the signal generator 71 which generates a brake release signal and turns on gate means 63. The brake release signal then actuates solenoid 53, opening three-way valve 51 to vent motive fluid through conduit 49 into ram 45. The ram 45 lifts the brake lever 39 to allow pay out of the fast end 27 of the cable. As the cable drum 29 starts to rotate, the cable drum monitor means 65 rotates much more rapidly and effects a signal via signal length modifier means 67 to render gate means 63 nonconductive, closing three-way valve 51 and venting the motive fluid to the atmosphere; allowing the spring 41 to return to brake lever downwardly to apply the brake to the drum and stop pay out of the cable. This cycle is repeated a plurality of times during the drilling operation, of course, to maintain a uniform weight-on-bit. In fact, it has been found preferable to employ a pulse generator as the signal generator 71. Thus, the brake release signal will comprise a plurality of discrete pulses of short time duration, as described hereinbefore. Each pulse, however, effects a full "on" brake release signal to avoid the disadvantages of the prior art and approach a perfect driller using manual operation.

45 In setting the control tension, a portion of the drill string weight is suspended from the travelling block 13. For example, if 32,000 pounds of weight is desired on the bit and the drill string weighs 160,000 pounds, then the drill bit will be placed on the bottom and slacked off until there is 128,000 pounds being supported by the travelling block 13, as determined by an appropriate conventional instrument; such as, a deadline monitor or a load cell in the hook support mechanism. With the 128,000 pounds being supported, the sensor means 59 is zeroed to establish the control tension in the cable. As the bit drills into the formation, there is a tendency for additional weight to be picked up by the cable, effecting increased tension on the deadline 25. Accordingly, the sensor means 59 will effect an output to indicate that additional cable should be payed out from cable drum 29. As indicated hereinbefore, the controller 69 employs the phase detector 73 to afford sensitive monitoring of the output from the sensor means 59. Similarly, the level detector 75 responds to output from phase detector 73 to start the pulse signal generator

running. Each pulse to the multivibrator; such as, a monostable multivibrator serving as the gate means 63; effects the brake release signal pulse output of the desired time duration. The time duration may be altered to effect the optimum control time duration by setting the calibrated dial 77, indicating a predetermined setting on a Helipot controlling the astable time period of the monostable multivibrator.

As the cable drum 29 begins to rotate, the wheel 79 and the rotary cam 83 rotate more rapidly, effecting rapid switching of the switch means 89. The rapid switch of the switch means 89 charges biasing capacitor 101 to the voltage that renders the transistor 97 conductive. The rate at which the capacitor is charged is proportional to the rate at which the switch means 89 is switched between first contact 109 effecting discharging and contact 111 effecting charging of the biasing capacitor 101. In any event, when the transistor is rendered conductive, it effects a resetting of the monostable multivibrator back to its stable state by appropriate conventional means. If the cable drum is in a worn region such that it begins to rotate more rapidly and pay the cable out more rapidly upon the release of the brake, the capacitor 101 is charged more rapidly and renders the transistor 97 conductive after a shorter time period, cutting short the brake release signal and reapplying the brake. Conversely, if the cable drum starts to rotate more slowly, as caused by an out-of-round condition, the switch means 89 is switched more slowly and the biasing capacitor 101 is charged more slowly. Consequently, there is a longer time interval before the transistor 97 is rendered conductive to stop the brake release signal. Thus, a proportional response is effected on the trailing edge of the brake release signal to compensate for any imperfections in the initial adjustment of the multivibrator, as effected by the setting of the calibrated dial 77. At the same time, all of the advantages of a full "on" brake or a full "off" brake are effected.

Another embodiment of this invention is illustrated in FIGS. 1 and 4 wherein the signal length modifier means 67 comprises serially connected variable time delay generator means 119 and switch means 121. As described hereinbefore, the switch means 121 comprises a switch that is responsively connected with the drum rotation monitor means 65 via rotary cam 83 and mechanical connections described hereinbefore, illustrated by dashed lines 85 and 123. Thus, after a brake release signal has effected release of the brake 37 and the cable drum 29 has started to rotate to pay out cable 27, closure of the switch means 121 is effected and the resulting signal is transmitted via the delay of the variable time delay generator 119 to the gate means 63 to stop the brake release signal. As illustrated, the switch means 121 is serially electrically connected with a power source (not shown) via conductor 127, a trigger means 129, the variable time delay generator 119 and the gate means 63 such as multivibrator 131. The switch means 121 may comprise any acceptable "on-off" switching device. Similarly, any conventional trigger means may be employed as trigger means 129. As illustrated, the trigger means 129 comprises a Schmitt trigger circuit for shaping the pulse effected by the switch means 121.

Any of the conventional delay generators that may be adjusted for time duration are acceptable as delay generator 119. As illustrated, the delay generator com-

prises a monostable multivibrator 135 and a differentiator for trailing edge 137. Specifically, the monostable multivibrator 135 has a Helipot arrangement, as described hereinbefore with respect to the monostable multivibrator employed as the gate means 63 and as illustrated by the calibrated dial 139. Thus, the calibrated dial 139 may be turned to a predetermined setting to effect, via suitable Helipot, a pulse output that has a predetermined time duration which will ultimately serve as the time delay. The differentiator for trailing edge 137 is a conventional circuit which converts the turning off of the pulse from the monostable multivibrator 135 into a positive going pulse suitable to turn off the multivibrator 131 serving as the gate means 63. As indicated hereinbefore, the multivibrator 131 is also preferably a monostable multivibrator that effects a pulse of a predetermined time duration for ensuring the stopping of the brake release signal even if the signal length modifier means 67 fails to stop the brake release signal. The monostable multivibrator 131 has, as indicated hereinbefore, a Helipot arrangement, indicated by calibrated dial 77 for varying the time interval of the pulses comprising the brake release signal. Thus, with this embodiment, the brake release signal may be manually adjusted at its front end to effect the desired time interval for the pulses comprising the brake release signal, and a manually adjustable feedback from the cable drum rotation monitor means employed to provide additional compensation for the inherent lag and operating characteristics of the brake and control systems.

In operation, a brake release signal is effected as described hereinbefore with respect to FIGS. 1-3. The brake is released, similarly as described hereinbefore, and the cable drum 29 starts to rotate to pay out cable. As it has rotated a short distance; for example, from a lineal distance of from one-half inch up to several inches, effected by proper sizing of the movement detecting wheel 79 ultimately driving the switch means 121; the switch means 121 is closed. Closure of the switch means 121 effects, via the Schmitt trigger circuit in trigger means 129, a pulse to turn on the monostable multivibrator 135. The monostable multivibrator 135 effects a pulse of a predetermined width, or time interval. Then the pulse is terminated. Upon the termination of the pulse, the differentiator for trailing edge 137 effects a signal which is passed to the multivibrator 131 to turn it off and stop passage of any brake release signal being sent to the brake release means.

Thus, it can be seen that the invention accomplishes the objects delineated hereinbefore and provides one or more of the desirable features not heretofore provided. Specifically, this invention employs the proven "on-off" approach to controlling the pay out of cable to maintain the proper weight-on-bit, while providing means at the front end and at trailing edge of the brake release signal to compensate for the inertia, lag, and dynamics of the braking system and the control system to eliminate over controlling.

Although the invention has been described with a certain degree of particularity, it is understood that the present disclosure has been made only by way of example and that numerous changes in the details of construction and the combination and arrangement of parts may be resorted to without departing from the spirit and the scope of the invention.

What is claimed is:

1. In apparatus for automatically controlling weight on the bit in a rotary drilling rig including:
  - a. cable drum for spooling the "fast" end of a tensioned cable bearing a portion of the weight of a drill string;
  - b. drum rotation monitor means responsively connectable with said drum for monitoring rotation thereof;
  - c. sensor means connected responsively with the tensioned "dead" end of said cable;
  - d. brake for said drum;
  - e. brake applying means connected with said brake for automatically restoring and maintaining said brake applied when said brake is not being released by a brake release means;
  - f. brake release means connected with said brake releasing said brake;
- the improvement comprising:
  - g. gate means connected with said brake release means for passing a brake release signal to said brake release means to fully release said brake and for terminating said brake release signal to fully apply said brake;
  - h. signal generating means comprising controller means and a signal generator connected with said sensor means and said gate means for generating a brake release signal and actuating said gate means to pass said brake release signal to said brake release means responsive to sensing of a cable tension greater than a predetermined control tension; said brake release signal being sufficient to effect a full release of said brake; and
  - i. signal length modifier means comprising a proportional response means connected with said drum rotation monitor means and said gate means for supplying to said gate means a signal responsive to both rate and degree of rotation of said drum causing said gate means to terminate passage of said brake release signal after a time interval the magnitude of which is inversely proportional to the rate at which said drum starts to rotate such that said brake is fully applied and fully released to avoid the disadvantages of partially releasing said brake; said proportional response means including a switch means, a Paschal-type filter network and a level sensor; said drum rotation monitor means being drivingly connected with said switch means that is connected into said Paschal-type filter network; said Paschal-type filter network being connected with said level sensor that is connected with said gate means.

2. The apparatus of claim 1 wherein said level sensor comprises an electronic switch means having means rendering it conductive; said electronic switch means being serially connected with said gate means and a power source for rendering said gate means nonconductive; and said switch means is a single-pole, double throw type, and is connected into said Paschal-type filter network comprising:

- a. a biasing resistor and capacitor serially connected between said means rendering said electronic switch means conductive and the center pole of said switch means;
- b. first resistor connected with the juncture of said biasing resistor and said biasing capacitor and with a first contact of said switch means so as to discharge said biasing capacitor at a first rate when

- said switch means connects said capacitor with said first contact;
- c. electrical common connected with the second contact of said switch means for charging said biasing capacitor at a second rate when said switch means connects said capacitor with said second contact; and
  - d. parallel-connected resistor and capacitor serially connected with said power source and the juncture of said means rendering said electronic switch means conductive and said biasing resistor; said capacitors and said resistors being chosen such that said second rate is greater than said first rate and said biasing capacitor is charged more rapidly with more rapid switching by said switch means, said biasing capacitor being charged to a voltage such that said electronic switch means is rendered conductive;
- whereby said brake release signal is terminated after a time interval that is shortened by more rapidly opening and closing said switch means as by rapid acceleration of said cable drum as it starts to rotate.
3. In apparatus for automatically controlling weight on the bit in a rotary drilling rig including:
    - a. cable drum for spooling the "fast" end of a tensioned cable bearing a portion of the weight of a drill string;
    - b. drum rotation monitor means responsively connectable with said drum from monitoring rotation thereof;
    - c. sensor means connected responsively with the tensioned "dead" end of said cable;
    - d. brake for said drum;
    - e. brake applying means connected with said brake for automatically restoring and maintaining said brake applied when said brake is not being released by a brake release means;
    - f. brake release means connected with said brake for releasing said brake;
  - the improvement comprising:
    - g. gate means connected with said brake release means for passing a brake release signal to said brake release means to fully release said brake and for terminating said brake release signal to fully apply said brake; said gate means being a multivibrator that is turned on by a signal generator and turned off by a proportional response means;
    - h. signal generating means comprising controller means and signal generator connected with said sensor means and said gate means for generating a brake release signal and actuating said gate means to pass said brake release signal to said brake release means responsive to sensing of cable tension greater than a predetermined control tension; said brake release signal being sufficient to effect a full release of said brake; and
    - i. signal length modifier means comprising a proportional response means connected with said drum rotation monitor means and said gate means for supplying to said gate means a signal responsive to both rate and degree of rotation of said drum causing said gate means to terminate passage of said brake release signal after a time interval the magnitude of which is inversely proportional to the rate at which said drum starts to rotate such that said brake is fully applied and fully released to avoid the disadvantages of partially releasing said brake.

4. The apparatus of claim 3 wherein said multivibrator is a monostable multivibrator for ensuring termination of said brake release signal and thereby providing a fail-safe, feature.

5. In apparatus for automatically controlling weight on the bit in a rotary drilling rig including:

a. cable drum for spooling the "fast" end of a tensioned cable bearing a portion of the weight of a drill string;

b. drum rotation monitor means responsively connected to said drum for monitoring rotation thereof;

c. sensor means responsively with the tensioned "dead" end of said cable;

d. brake for said drum;

e. brake applying means connected with said brake for automatically restoring and maintaining said brake applied when said brake is not being released by a brake release means;

f. brake release means connected with said brake for releasing said brake;

the improvement comprising:

g. gate means connected with said brake release means for passing a brake release signal to said brake release means to fully release said brake and for terminating said brake release signal to fully apply said brake; said gate means being a bistable multivibrator;

h. signal generating means comprising controller means and a signal generator connected with said sensor means and said gate means for generating a brake release signal and actuating said gate means to pass said brake release signal to said brake release means responsive to sensing of cable tension greater than a predetermined control tension; said brake release signal being sufficient to effect a full release of said brake; said signal generator when energized producing a continuous signal that turns on said bistable multivibrator to effect said brake release signal; and

i. signal length modifier means connected with said drum rotation monitor means and said bistable multivibrator serving as said gate means for turning off said bistable multivibrator responsive to both rate and degree of rotation of said drum causing said bistable multivibrator to terminate passage of said brake release signal; whereby said brake is fully applied and fully released to avoid the disadvantage of partially releasing said brake.

6. In apparatus for automatically controlling weight on the bit in a rotary drilling rig including:

a. cable drum for spooling the "fast" end of a tensioned cable bearing a portion of the weight of a drill string;

b. drum rotation monitor means responsively connectable with said drum for monitoring rotation thereof;

c. sensor means connected responsively with the tensioned "dead" end of said cable;

d. brake for said drum;

e. brake applying means connected with said brake for automatically restoring and maintaining said brake applied when said brake is not being released by a brake release means;

f. brake release means connected with said brake for releasing said brake;

the improvement comprising:

g. gate means connected with said brake release means for passing a brake release signal to said brake release means to fully release said brake and for terminating said brake release signal to fully apply said brake; said gate means being a monostable multivibrator that produces a plurality of discrete pulses of a first time duration, each said pulse effecting passage of said brake release signal and termination thereof when not otherwise terminated;

h. signal generating means comprising controller means and signal generator connected with said sensor means and said gate means for generating a brake release signal and actuating said gate means to pass said brake release signal to said brake release means responsive to sensing of cable tension greater than a predetermined control tension; said brake release signal being sufficient to effect a full release of said brake; and

i. signal length modifier means connected with said drum rotation monitor means and said gate means for supplying said gate means a signal responsive to both rate and degree of rotation of said drum causing said gate means to terminate passage of said brake release signal; whereby said brake is fully applied and fully released to avoid the disadvantages of partially releasing said brake; said signal length modifier means being operable to render said monostable multivibrator nonconductive responsive to rate and degree of rotation of said drum to shorten said first time duration as needed to effect optimum control of the weight-on-bit and alleviate difficulties with over controlling.
